United States Patent Office

Des. 182,147
Patented Feb. 18, 1958

182,147

TRACTOR

Walter F. Strehlow, Wauwatosa, Wis., assignor to Allis-Chalmers Manufacturing Company, Milwaukee, Wis., a corporation of Delaware

Application December 31, 1956, Serial No. 44,372

Term of patent 14 years

(Cl. D14—3)

Fig. 1 is a perspective side view of a tractor showing the new design.

Fig. 2 is a perspective three-quarter view.

Fig. 3 is a perspective three-quarter view showing the side of the tractor opposite to that shown in Fig. 2.

Fig. 4 is a rear perspective view.

I claim:

The ornamental design for a tractor, as shown.
